CLAIM

The ornamental design for a handle, as shown and described.

DESCRIPTION

FIG. 1 is a left, top, front perspective view of a handle embodying my new design;

FIG. 2 is a front elevational view thereof, the rear elevational view being a mirror image of the front elevational view shown;

FIG. 3 is a top plan view thereof;

FIG. 4 is a bottom plan view thereof;

FIG. 5 is a right side elevational view thereof; and,

FIG. 6 is a left side elevational view thereof.

The broken line representation of a hole in FIG. 4 is for the purpose of illustration only, and forms no part of the claimed design.
